UNITED STATES PATENT OFFICE

2,405,432

COOLING APPARATUS

Herman W. Kleist, Chicago, Ill., assignor to Dole
Refrigerating Company, Chicago, Ill., a corpora-
tion of Illinois

Original application March 20, 1939, Serial No.
262,910. Divided and this application April 6,
1942, Serial No. 437,742

3 Claims. (Cl. 62—89)

1

This invention relates to cooling apparatus and has for its object to provide a new and improved device of this description.

The invention has as a further object to provide a storage room or system for the articles to be cooled, wherein there is a series of flat thin plates with coils in them, suspended in the storage room, the coils being connected with a compressor, a refrigerant material being circulated from the compressor through these coils and back to the compressor.

The invention has as a further object to provide a cooling apparatus consisting of a comparatively thin plate made of sheets of metal hermetically sealed, with a pipe therein formed into a coil and having flat sides which engage the sheets of metal, air being exhausted from between the sheets to cause the atmosphere on the outside to press them tightly against the pipe.

The invention has further objects which are more particularly pointed out in the accompanying description.

This is a divisional case taken from my original application Serial Number 262,910, filed March 20, 1939.

Referring now to the drawings,

Fig. 1 is a side elevation of one form of device embodying the invention and illustrating the first plate of a series;

Fig. 2 is a sectional view on an enlarged scale, with parts omitted, taken along the line 2—2 of Fig. 1;

Fig. 3 is a sectional view through the nipple used for exhausting air from the plate;

Fig. 4 is a horizontal section showing diagrammatically a locker room provided with the cooling plates;

Fig. 5 is a view showing means of connecting the cooling plates in series.

Like numerals refer to like parts throughout the several figures.

Referring now to the drawings, there is illustrated a cooling plate made up of sheets 1 and 2 of metal, the sheets being fastened together so as to form a chamber which will be hermetically sealed. One of the constructions for this purpose is herein shown wherein one of the sheets, such, for example, as the sheet 2, has its edge bent at an angle to its face all the way around, to provide the wall 3 extending all the way around, this wall having a flange 4 preferably integral therewith, which engages the sheet 1. The flange is hermetically sealed to this plate in any desired manner, as by welding. The welding is preferably done electrically by running an electric welding

2

device around the plate in engagement with the flange 4 and the part of the sheet with which the flange 4 engages.

In between the sheets there is provided a pipe 5 which instead of being circular has its sides flattened, as shown at 6 and 7. The sheets 1 and 2 engage these flattened sides 6 and 7 so as to have a large area of contact with the pipe, as will be seen by examining Fig. 2. Air is exhausted from the chamber formed by the sheets 1 and 2 by applying an air exhausting device to the connection or nipple 8 which is connected with the space between the sheets 1 and 2. This connection or nipple may be of any desired form. I have illustrated in Fig. 3 a simple form for this purpose wherein the nipple has an end 9 which projects through the wall 3 and into the space between the sheets 1 and 2. This nipple has a recess 10 which is threaded at one end to receive the threaded plug 11. Within this recess is a valve 12, shown as a ball. There is a passageway 13 connecting the recess 10 with the interior of the plate and the valve 12 controls this passageway.

When it is desired to exhaust the air from the interior of the plate, the plug 11 is removed and a connection is made with an air exhausting device. When the proper amount of air is exhausted, the air exhausting device is disconnected from the nipple, the valve 12 maintaining the vacuum in the plate. The plug 11 is then preferably sealed so as to insure the maintenance of the vacuum. When air is exhausted from between sheets 1 and 2, the pressure of the outside atmosphere presses these sheets tightly against the flat portions 6 and 7 of the pipe 5, so as to secure and maintain an intimate contact with this pipe. An eutectic solution of any of the usual types 8a may be used to partially fill the space between the plates 1 and 2 (see Fig. 2). The plates may be used with or without the eutectic, which may be a salt solution.

When the device is in use a refrigerant is passed through the pipe 5. This refrigerant may enter the pipe by means of the inlet 14 and be discharged from the pipe by means of the outlet 15. The inlet and outlet are connected to any suitable refrigerating machine or apparatus and any desired refrigerant material may be passed through the pipe 5.

This construction provides a large area of contact between the pipe of the coil and the sheets of metal, so as to increase the cooling efficiency of the device and also provides a thin cooling device and at the same time increases its efficiency.

This construction is particularly adapted for use in storage lockers in locker storage rooms. In Fig. 4 I have shown one form of locker room provided with the cooling plates. In this construction there are a series of the vacuum plates 1a, which may be supported in any desired manner, preferably from the ceiling. These plates are the plates illustrated in Fig. 1, and they are connected in this particular construction in series. I have only attempted to show more or less diagrammatically one form of locker room. In this construction there are a series of locker room corridors 2a, 2b, etc., from which the material to be cooled is placed in any suitable lockers. The cooling plates 1a are preferably located at the ceiling, that is, suspended from the ceiling, and there are doors 3a, as shown, for access to the locker rooms. I have illustrated an entrance 4a to the main room with a passageway 5a along the side, the doors 3a for the locker rooms communicating with this passageway so that there is no access to the locker rooms or the room 6a directly from the outside of the main room. The connection of the cooling plates in series is illustrated in Fig. 5, wherein the first plate of the series 1a is connected by a pipe 17 with the expansion valve 18. The expansion valve is connected by a pipe 19 with the liquid line 20 from the compressor. The ends of the coils in the several cooling plates are connected together by the pipes 21, 22, 23, 24 and 25. The last cooling plate 1a is connected to the suction line 26, which leads back to the compressor. It will be noted that this construction connects all the coils in the plates in series. The usual automatic device for closing the expansion valve 18 is used, which consists of a bulb 27 connected to a pipe 28 and which leads to the valve 18. When the temperature lowers below a predetermined point, this bulb acts to cause the expansion valve to close and when the temperature rises above a predetermined point, it acts to cause the expansion valve to open.

In Figure 5 is diagrammatically illustrated a refrigerating cycle in which the cold plates 1a are included. I illustrate for example a compressor 50 actuated by a motor 51. 52 indicates any suitable condenser and 53 any suitable receiver. It will be understood that any suitable refrigerating unit may be employed, the mechanical structure herein illustrated being for the purpose of illustration.

The use and operation of my invention are as follows:

In carrying out the invention, the lockers 1a contain the food which is in a frozen condition. The cooling plates 1a are preferably placed on opposite sides of these lockers, the lockers being arranged so that the cold air can enter and pass therethrough so as to come into contact with the frozen foods and maintain such frozen foods in a frozen condition. The plates 1a are supported from the roof and there is a passageway beneath them entered by means of the doors 3a. The parties owning the lockers pass through these doors into the passageway opposite their particular lockers so that they can enter the lockers and remove the frozen food.

It will be noted that the doors through which

these passageways are entered do not communicate with the outside atmosphere or with any warm atmosphere. By means of this arrangement, the parties renting the lockers may enter the main room and then may pass through one of the doors 3a into the passageway opposite their lockers and can remove whatever food desired and take it home.

By means of this construction the food in the locker may be maintained in a frozen condition for a long period and until it is removed therefrom.

I claim:

1. A cooling system comprising a storage room for the articles to be cooled a plurality of food receiving lockers in said room, a passageway between the lockers by means of which the users secure access to said lockers, a plurality of cooling plates supported in said storage room exterior to said lockers, said cooling plates each consisting of imperforate sheets of metal connected together, with a coil therein having flat sides which are tightly engaged by said sheets, the coils in said several plates being connected in series, and means for supplying a refrigerant to the coil in the first plate of the series and for circulating it successively through the coils in the remaining plates of the series, the plates being so constructed and arranged that the opposite sides of each plate are in contact with the air in the storage room.

2. A cooling system comprising a storage room for the articles to be cooled, said room having a plurality of corridors with lockers lining said corridors, a plurality of cooling plates suspended in the upper part of said storage room, in groups arranged in the upper portions of said corridors, each said cooling plate consisting of imperforate sheets of metal connected together and sealed to form a hermetically sealed space between them, a coil through which refrigerant material is passed, located in each said plate, the plates lying in vertical planes extending longitudinally along and in vertical alignment with said corridors, the sheets of each plate being held in intimate engagement with the sides of the coils in said plate, and means for circulating refrigerant material through the coils of said plates, the plates being so constructed and arranged that the opposite sides of each plate are in contact with the air in the storage room.

3. A cooling system comprising a storage room for the articles to be cooled, said room having a plurality of corridors with lockers lining said corridors, a plurality of cooling plates suspended in the upper part of said storage room, in groups arranged in the upper portions of said corridors, each said cooling plate consisting of imperforate sheets of metal connected together and sealed to form a hermetically sealed space between them, means for circulating a volatile refrigerant through said plates, the plates lying in vertical planes extending longitudinally and in vertical alignment with said corridors, the plates being so constructed and arranged that the opposite sides of each plate are in contact with the air in the storage room.

HERMAN W. KLEIST.
